COMBINED CAN OPENER AND CLOCK

Harold Weiss, Fort Lee, N.J., assignor to Sunmade Electric Corp., New York, N.Y., a corporation of New York

Filed Feb. 13, 1970, Ser. No. 21,437

Term of patent 14 years

Int. Cl. D8—02

U.S. Cl. D8—34

FIG. 1 is a front perspective view of a combined can opener and clock showing my new design; and
FIG. 2 is a rear perspective view thereof.

I claim:

The ornamental design for a combined can opener and clock, as shown.
